UNITED STATES PATENT OFFICE.

JOHN Q. FLINT, OF WILTON, NEW HAMPSHIRE.

METHOD OF CONSTRUCTING WAGON-SEATS.

SPECIFICATION forming part of Letters Patent No. 369,510, dated September 6, 1887.

Application filed May 11, 1886. Serial No. 201,933. (No model.)

To all whom it may concern:

Be it known that I, JOHN Q. FLINT, of Wilton, county of Hillsborough, and State of New Hampshire, have invented new and useful 5 Improvements in the Construction of Wagon- Seats, of which the following is a specification, reference being had to the annexed drawings, forming a part thereof, in which—

Figure 1 is a side elevation. Fig. 2 is a rear 10 view. Fig. 3 is an inverted plan view.

Similar letters of reference indicate corresponding parts in the different figures of the drawings.

The object of my invention is to provide 15 simple and efficient means for bending the rails of seat-backs and securing them to the sawed back-piece.

My invention consists in a method of securing 20 the bent rail to the lower edge of the sawed back-piece, as hereinafter fully described, and pointed out in the claim.

In carrying out my invention I provide a 25 form, A, which is adapted to receive the sawed part B of the buggy-back, which is temporarily secured to the form by screws passing through the form into the back. The end of the form projects beyond the end of the back, and is rabbeted to produce a bearing-surface for the rail, which is bent around the form and 30 along the lower edge of the back B, as will be hereinafter more fully described.

To the ends of the curved form A is secured 35 the cross-bar C, having slots *a* cut in opposite ends and slots *b* cut down its outer face, constituting forms for the ends of the seat-rail. The curved form A and the bar C are connected together by tongue-and-groove joints D D', which permit of expanding the forms for

seats of different lengths. The bar C is secured to the form A by bolts *d*, which permit 40 of removing the bar from the form. The ends of the bars *c*, of which the seat-rail is formed, are received in the slots *b a*, and are scarfed or halved together at their adjoining ends at the center of the back-piece B, and are secured to 45 the lower edge of the back by means of nails or screws and glued, and to facilitate the bending of the adjoining ends of the bars *c* they are split longitudinally. The ends of the bars *c* are brought into contact with the back-piece 50 B by means of clamps of the usual form, and they are held in this position until the rail has become thoroughly dry and its form fixed, when the screws which hold the back-piece B to the form A are removed, and the screws *d*, which 55 hold the bar C to the front of the form A, are also removed, and the bars *c*, with the back, may be removed and afterward finished up in the usual way.

Having thus described my invention, what I 60 claim as new, and desire to secure by Letters Patent, is—

The method of connecting the bent rail of a 65 wagon-seat with the sawed back-piece, which consists in securing the back-piece to a suitable form, bending the parts of the rail over the form and along the edge of the back-piece, clamping or otherwise securing the rail to the edge of the back-piece, and finally removing the back-piece and rail together from the form, 70 substantially as herein shown and described.

JOHN Q. FLINT.
